The ornamental design for a crew neck undergarment as shown and described.

DESCRIPTION

FIG. 1 is a front perspective view of the crew neck undergarment. The undergarment is symmetrical from left to right.

FIG. 2 is a rear perspective view of the crew neck undergarment. The undergarment is symmetrical from left to right; and,

FIG. 3 is a top plan view of the crew neck undergarment. The broken lines shown in the drawings are for illustrative purposes and form no part of the claimed design.
